G. D. DUDLEY.

Caster-Stands.

No. 134,738.

Patented Jan. 14, 1873.

UNITED STATES PATENT OFFICE.

GEORGE D. DUDLEY, OF LOWELL, MASSACHUSETTS, ASSIGNOR TO EDWARD P. WOODS, DAVID SHERWOOD, AND CYRUS H. LATHAM, OF SAME PLACE.

IMPROVEMENT IN CASTER-STANDS.

Specification forming part of Letters Patent No. 134,738, dated January 14, 1873.

To all whom it may concern:

Be it known that I, GEORGE D. DUDLEY, of Lowell, in the county of Middlesex and State of Massachusetts, have invented a new and Improved Caster or Stand for Holding Perfumery and other Bottles, of which the following is a specification:

Nature and Objects of the Invention.

My invention relates to casters or holders for bottles; and the invention consists in a novel construction and combination of parts, which have for their object to make a cheap, durable, beautiful, and ornamental article of manufacture in twisted wire.

Description of the Drawing.

Figure 1 is a perspective view of a three-hole caster or stand. Fig. 2 is a perspective view of a three-hole stand. Fig. 3 is a perspective view of a four-hole stand. Fig. 4 is a perspective view of a four-hole stand, the bottle-holders being square.

General Description.

These stands are made up from twisted wire, and consist of a frame, A B, mounted upon legs C, and having bottle-rings a combined with a

rest or seat, b, for the end of the bottle, and provided with a handle to lift and move the same. The parts are secured together by clinch-joints or metal clasps c, and, when complete, the whole is immersed in metallic bath and coated with tin, silver, &c., as may be desirable.

The construction of these stands will be readily understood from an inspection of the drawing.

In the drawing I have shown four different-shaped stands, and these shapes or styles can be enlarged to take any desired number or shape of bottles by additions and duplications of the necessary parts.

Claim.

I claim—

As a new article of manufacture, a stand for holding bottles made of twisted wire, the said stand having a series of holders, a, and a supporting ring or rest, b, for the bottle, substantially in the manner described and specified.

GEORGE D. DUDLEY.
